UNITED STATES PATENT OFFICE.

ARTHUR S. BALDWIN, OF BALTIMORE, MARYLAND.

DOUBLE SAFETY PERCUSSION-FUSE.

1,316,131.

Specification of Letters Patent. Patented Sept. 16, 1919.

Application filed November 23, 1916. Serial No. 133,059.

To all whom it may concern:

Be it known that I, ARTHUR S. BALDWIN, a citizen of the United States, residing at Baltimore, in the State of Maryland, have 5 invented certain new and useful Improvements in Double Safety Percussion-Fuses, of which the following is a specification.

This invention relates to an improved safety fuse device for shells or projectiles 10 and has particular reference to an improved plunger construction that will be normally held in a safety position to prevent accidental explosion, during handling and which will automatically assume an armed 15 position when subjected to the shock occasioned by the discharge of the shell from a gun.

The present invention is directed to the safety elements of the device and to the 20 certain shifting of those elements from the safety to the armed position when the shell is fired so that the chances of failure to explode after firing, will be reduced to a minimum.

25 The invention is illustrated in the accompanying drawings, wherein,—

Figure 1, shows in longitudinal section, a fuse case or stock for the point or nose end 30 of a shell or projectile and shows the improved devices thereof in the safety position.

Fig. 2, illustrates a cross-sectional detail through the same,—the section being taken on the line 2—2 of Fig. 1.

Fig. 3, shows a longitudinal section 35 through the fuse case or stock with the improved devices in the armed position, and

Fig. 4, illustrates a longitudinal section 40 through a fuse case or stock embodying the invention and which is designed for application to the base of a shell or projectile.

Referring to the drawing by numerals, 5, 45 designates the fuse case or stock, which in the form illustrated in Fig. 1, is provided with a tapered head or nose, 6, and is also provided with circumferential screw threads 7, by means of which it may be readily attached to the end of a shell or projectile body of any well-known form, and therefore not illustrated in the drawing. This

50 case or stock is provided with an interior longitudinal chamber 8, that is circular in cross-section and which is closed at its inner end by means of a circular cap 9. In the present instance this cap has a reduced 55 circumferential wall 10, and the larger end

thereof is inserted in the inner end of the case or stock and seats against an annular shoulder 11, provided on the interior of the case. The inner rim-edge 12, of the case-wall is then contracted about the tapered 60 wall of the cap and locks the same in place.

The cap 9 is provided with one or more passages 13 extending therethrough so their inner ends will open into the chamber of the shell or projectile proper in a well- 65 known manner.

The interior of the chamber 8, is provided with a cylindrical plunger body 14, which latter is sufficiently smaller than the chamber in diameter to afford a freedom of 70 movement when the body is freed. This plunger body has a central cavity 15, extending inwardly from one end thereof, and at opposite sides of said cavity, the wall of 75 said body has a bayonet slot 16.

Each bayonet slot is guarded at the bend, between its longitudinal and lateral portions by a lug 17, for a purpose presently to be explained.

A pin 18, extends crosswise of the fuse 80 case or stock and has its ends retained in perforations 19, at diametrically opposite sides of the case or stock body, as clearly shown in Fig. 2, of the drawing. This cross-pin is rigid with the case or stock and normally extends diametrically through the 85 lateral bends of the bayonet slot of the plunger body, and also through the central cavity 15, of the latter.

By reference to Fig. 1 of the drawing it 90 will be seen that the cross-pin is shown seated in a concavity 20, that is provided in the lateral bend of the bayonet slot and at the side of the lug 17, and thus the plunger body is normally held against rotation 95 in the chamber 8, independently of the case or stock and is also held against forward movement in said chamber. This position of the plunger body is therefore the safety position, because firing cannot take place as 100 long as the plunger is held against forward movement in the chamber 8.

In order to maintain the plunger body in the safety position by retaining the cross-pin in the concavity 20, I provide a yielding device, in the present instance a coiled spring 21, which presses against the slotted end of the plunger and holds the latter in locked engagement with the cross-pin. 105 This spring 21, has a plurality of coils and 110

one end of the spring enters the end of the plunger body while the other end 23, thereof is held rigidly with respect to the case or stock. In addition to the pressure longitudinally on the plunger body, the spring is wound sufficiently to exert a torsional strain on the plunger body, for a purpose which will also presently be explained.

In the formation of these safety fuse devices it is obvious that one part must carry the primer while another carries a firing pin. In so far as the present invention is concerned this is immaterial, for as illustrated in Fig. 3, the primer 24, is shown as carried by the movable plunger body and the firing pin 25, is located on the case or stock at the end of the chamber 8, while in Fig. 4, the firing pin 26, is formed on the plunger body and the primer 27, on the cap, which closes the inner end of the chamber 8.

In Fig. 3, the primer 24, is located over the central cavity 15, in the body to allow the gases generated by the detonation of the primer to pass through said chamber and through the passage or passages 13, of the cap 9, to the explosive charge in the shell or projectile.

In practice it is immaterial whether the fuse device be attached at the point or base of the shell or projectile, the operation being the same in either case.

When the fuse device is assembled and ready for attachment to a shell or projectile, the plunger body 14, is held in the chamber 8, by the cross-pin 18, seating against the concave recess 20, in the lateral bend of the bayonet slot, which prevents forward movement of the body.

The body and pin are maintained in position by means of the spring 21, which presses the body forward into locked engagement with the said pin. Inasmuch as the body cannot move forward when engaged by the pin, as in Fig. 1, the body is said to be held in the safety position.

The spring 21, in addition to exerting a forward pressure on the body 14, is also somewhat twisted to exert a torsional strain on said body, which tends to rotate it, but which is held against rotation because of the lug 17, on the body engaging the side of the cross-pin 18.

The assembled fuse device is screwed into the shell or projectile, the threads 7, on the case or stock serving to effect this connection.

Thus it will be seen that when the fuse device is attached to the shell or projectile the plunger body 14, is in a safety position and is locked therein by means of the bayonet slot and pin and also by the action of the spring, so that during shipment, handling or loading the shell into a gun, the fuse device is locked in the safety position and

will not release upon receiving accidental jars such as would be caused by dropping the shell during handling.

When the shell is discharged from a gun, however, the case or stock of the fuse device at once assumes the velocity of the shell, while the plunger body which only has a yielding attachment to the case or stock will momentarily lag behind so that the cross-pin 18, which is rigid with the case or stock will travel forward with the latter and move away from the side of lug 17. As soon as the pin clears the lug the torsional strain of the spring 21, will cause the plunger body to slightly rotate and bring the pin and the longitudinal passage portions of the bayonet slot into register so that the plunger body will be freed and moved to what is termed the armed position. As the velocity of the plunger body picks up and equals that of the shell and fuse case, it will be free to move longitudinally in the chamber 8, so that when the velocity of the shell and fuse case or stock is checked, as when striking an object, the plunger body may continue its forward movement so as to bring the firing pin and primer together and effect ignition to produce the desired explosion.

Having described my invention what I claim and desire to secure by United States Letters Patent is:—

1. In a safety fuse device the combination with a case having a chamber therein, of a plunger-body in said chamber; a pin rigid with the case and extending diametrically and freely through the plunger-body to normally hold the latter in a safety position in the chamber and means for effecting a disengagement of the pin and plunger-body said means being carried by the case and becoming operative when the fuse device is projected in a shell.

2. In a safety fuse device the combination with a case having a chamber that is circular in a cross-wise direction, of a plunger-body in said chamber, said body having a bayonet slot that extends cross-wise thereof and opens at both sides thereof; a pin rigidly carried by the case and extending all the way through the bayonet slot in the body, and means in the case for turning the body with respect to the pin when the fuse device is projected.

3. In a safety fuse device the combination with a case having a chamber that is circular in a cross-wise direction, of a plunger body in said chamber, said body having a diametrically extending slot therein with an off-set at one end thereof; a pin extending diametrically across the chamber and through said slot for normally engaging the off-set in said slot in the body, and a spring for pressing the wall of the off-set portion of the body slot against the pin.

4. In a safety fuse device for shells or

projectiles the combination with a case having a longitudinal chamber therein, of a plunger body in said chamber and having a bayonet slot extending therein from one 5 end thereof; a pin extending through the bayonet slot of the plunger body and engaged in the case and a spring at the slotted end of the plunger body to press the latter

against the pin and to apply a torsional strain on the body for the purpose set forth. 10

In testimony whereof I affix my signature in the presence of two witnesses.

ARTHUR S. BALDWIN.
